[57] **CLAIM**

The ornamental design for a hand held mirror, as shown and described.

DESCRIPTION

FIG. 1 is a rear perspective view of a hand held mirror showing my new design;

FIG. 2 is a front elevational view thereof;

FIG. 3 is a bottom plan view thereof;

FIG. 4 is a rear elevational view thereof;

FIG. 5 is a left side elevational view thereof, the side opposite being a mirror image of the side shown;

FIG. 6 is a top plan view thereof;

FIG. 7 is a cross sectional view taken on line 7—7 of FIG. 4; and,

FIG. 8 is a cross sectional view taken on line 8—8 of FIG. 4.

*Fig. 1**Fig. 2**Fig. 3**Fig. 4**Fig. 5**Fig. 7**Fig. 8**Fig. 6*
